SHAKER CONVEYER

Ernst R. Bergmann and William W. Sloane, Chicago, Ill., assignors to Goodman Manufacturing Company, Chicago, Ill., a corporation of Illinois

Application March 10, 1951, Serial No. 214,934

4 Claims. (Cl. 198—220)

1

This invention relates to improvements in extensible feeding heads for shaker conveyors, and more particularly to sluing mechanisms for such devices.

The principal object of the invention is to provide a simple, efficient and positively actuated draft mechanism associated with the conveyor and operated by the shaking motion of the latter, for selectively drawing in flexible cables suitably anchored to abutments at opposite sides of the conveyor, whereby the loading end of the conveyor may be slewed or pivotally swung at will toward one side or the other for loading loose material at varying angles.

A further object is to provide an improved actuating mechanism for devices of the character described, operating in conjunction with the anchored swivel or articulated joint of the conveyor trough line, to effect a more positive and continuously available sluing action, as desired.

A further object is to provide a draft mechanism of the character described, including means for maintaining the sluing cables in taut condition at all times, regardless of whether the feeding head is being actuated.

The invention may be best understood by ref-

ference to the accompanying drawings, in which Figure 1 is a plan view showing a shaker con-

Figure 11 is a plan view of a conveyor installed in the working room of a mine, and illustrating the method of use of a sluing mechanism in accordance with the invention:

Figure 2 is an enlarged side view of the front end of the conveyor shown in Figure 1, with parts broken away;

Figure 3 is an enlarged detailed section taken on line 3—3 of Figure 2;

Figure 4 is a fragmentary plan view of the main parts of the sluing mechanism;

Figure 5 is an enlarged plan view of the drum winding mechanism forming a principal part of the invention, with parts broken away to show certain details thereof;

Figure 6 is a detailed section taken on line 6-6 of Figure 5:

Figure 7 is an exploded perspective view of part of the clutch employed in the mechanism.

Figure 8 is an enlarged end view of the manual control and guide means adapted for attachment to the conveyor.

Figure 9 is a plan view of the attachment shown in Figure 8, with parts shown in section; and

2

Figure 10 is a fragmentary section of the one-way clutch mechanism.

Referring now to details of the embodiment of my invention shown in the drawings, Figure 1 shows a main trough 10 of a shaker conveyor, connected through a swivel or articulated joint 11 to a trough section 12 having a loader head indicated at 13 connected at its forward or inby end. The trough 10 is reciprocably driven as usual by a shaker drive generally indicated 9.

The swivel or articulated joint 11 is of the kind commonly employed in shaker conveyors, including a base 14 having sockets 15, 15 at opposite ends of a cross bar 16 for reception of mine jacks (not shown) to anchor said base to the ground. The cross bar 16 also has a pair of roller supports 17, 17 on which the swivel joint 11 is slidably mounted, as usual, to permit the usual shaking motion of the main trough 10 and its swivel connection relative to the anchored base 14. Further details of the swivel 11 and its base 14 and roller supports 17, 17 need not be shown nor described, as they form no part of the present invention, excepting to point out that a bracket 19 is fixed to the cross bar 16 of the base, having a link 20 pivotally connected thereto, which extends forwardly to form part of the actuating means for the sluing mechanism, as will presently be described.

30 The loading head 13 is also of a well-known type commonly known as a duckbill, wherein an extensible trough 21 having a shovel 22 fixed on its front or inby end, is telescopically mounted with respect to the trough 12. A feeder head 23 is secured to the front end of the trough 12 and is adapted to ride on the extensible trough 21 intermediate its ends during telescopic movement of the two troughs. The extensible trough 21 is supported on the ground at its front end by the shovel 22 and at its rear end by an upright support 24 on a shoe 25. The latter trough is thus supported in frictional engagement with the ground, so as to tend to remain stationary excepting when engaged by grip blocks 26, 26 carried on the feeder head 23. The relative extension or retraction of the two troughs 12 and 21 is controlled as usual by manipulation of the grip blocks 26 in proper timed relation to the shaker motion of trough 12. The gripping action of blocks 26 may be manually controlled through any well-known linkage mechanism on the feeder head, which need not be described nor shown in further detail as it forms no part of the present invention.

55 Referring now more particularly to the details

of the sluing mechanism, a pair of take-up or winding drums 27 are mounted at opposite sides of a supporting frame 28, fixed to an intermediate trough section 29. In the form shown herein, the latter trough section forms part of the trough 12 and is interposed in the conveyor trough line between the upper swivel joint 11 and that forward portion of the trough 12 on which the extensible trough 21 is telescopically mounted. The intermediate trough section 29 is detachably connected at its rear end to the swivel joint 11 by eyes 30 and bolts 31, and at its front end to the main part of the trough section 12 by eyes 32 and bolts 33, in the manner usually employed for connecting adjacent trough sections.

The supporting frame 28 for the winding drums 27 includes a bottom plate 34 in spaced relation beneath the intermediate trough section 29 and extending beyond the latter at opposite sides thereof, and a top plate 35 fixed to and extending from the opposite side walls of said trough section.

Details of the winding drums 27 and their actuating mechanism are shown in Figures 3 to 7. Each winding drum has a sluing cable 36 wound thereon, with a free end adapted to be extended for anchoring to a fixed abutment at one side of the conveyor, so as to swing the front end of the feeder head and associated parts of the conveyor bodily about the swivel joint 11 when said drum is driven positively in the proper direction.

The link 28 which is pivoted at its rear end to the anchored cross bar 16 of swivel 11, as previously described, has its front end pivoted to an elongated rack bar 37, slidably mounted longitudinally of the supporting frame 28 beneath and centrally of the intermediate trough section 29. Said rack bar has a pair of racks 38, 39 along opposite sides thereof, having toothed engagement with idler pinions 39, 39 pivotally supported on frame 28 at opposite sides of the rack bar 37. Each of the pinions engages similar gear sectors 40 on a drive disc 40a surrounding a hub portion 40b of an annular drive member 41, keyed on the lower end of a drive sleeve 42. The drive member 41 is driven from drive disc 40a through a load-limiting device, herein consisting of an adjustable friction band 41a carried by the drive disc and engaging the periphery of said drive member.

Each drive sleeve is rotatably mounted on bearings 43, 44 at the upper and lower ends of an upright supporting shaft 45, suitably fixed at its upper and lower ends in the top plate 35 and the bottom plate 34 of frame 28.

The drive sleeve of each of the two winding mechanisms at opposite sides of the frame 28 has a clutch sleeve 46 rotatably mounted thereon with a pair of vertically spaced bearings 47, 47. The clutch sleeve 46 has winding drum 27 rotatably mounted on its upper end, with annular bearings 48, 48 interposed therebetween.

The clutch sleeve 46 is driven from drive sleeve 42 by a one-way clutch 49 located between the spaced outer friction bearings 47, 47. This one-way clutch may be of any suitable construction; in the form shown in Figure 10 consisting of a plurality of sprags 50 surrounding the drive sleeve 42. These sprags are arranged to be rocked into frictional driving engagement with the clutch sleeve 46 only when the drive sleeve 42 is being rotated in the direction to wind its sluing cable 36 on the drum 27. The sprags 50 are normally held in approximate circumferential alignment by a pair of continuous annular coil springs 51 passing through grooves 52 on the upper and

lower faces of the sprags. The form of one-way clutch mechanism including sprags 50 is of a type well known in the art so further details thereof need not be described herein.

5 The clutch sleeve 46 has a plurality of elongated clutch teeth 53 projecting axially at its lower end which engage in apertures 54 formed in a clutch disc 55. The latter disc has vertical sliding movement on the upper hub 56 of the drive member 41. Said clutch disc has a plurality of clutch teeth 57 on its upper face adapted for engagement with clutch teeth 58 on the lower face of drum 27 when said clutch disc is shifted to its uppermost position, through a clutch shifting mechanism which will hereinafter be more fully described.

10 15 The clutch sleeve 46 also has an annular collar 59 formed integrally therewith of slightly less diameter than the clutch teeth 53 on the drum. A friction disc 60 of suitable material, such as asbestos fiber, is interposed between the collar 59 and the under face of the drum, so that said drum is frictionally engaged by disc 60 at all times.

20 25 Yielding brake means are also provided for holding the drum against unwinding and urging the latter into frictional engagement with the friction disc 60. In the form shown, this brake means consists of friction pads 61, herein two in number, each carried on a stem 62, yieldably urged against the upper face of the drum as by a coil spring 63 in an auxiliary housing 64 mounted on the top plate 35.

30 35 The two clutch discs 55 for the drums 27 on opposite sides of the conveyor are each shifted by a shifter fork 90, including arms 65, 65 fixed to a pivot rod 66 and having shifter members 67, 67 at their ends engaged in a groove 68 in the periphery of said clutch discs. Each of said pivot rods 66 is mounted for rocking movement on ears 40 69, 69, herein fixed to the outer sides of the trough. In the form shown herein, the two pivot rods 66 are fixed at their forward ends to tubular torsion rods 70 which extend forwardly along opposite sides of the trough section 12 to a manual control mechanism 71 on the feeder head 23, adjacent the control devices for extending or retracting the extensible trough 21. The tubular rods 70 are suitably supported for rotation in bearing supports 72 mounted on said feeder head. Bell cranks 73 are fixed on the front ends of said tubular rods. Said bell cranks each has an outwardly extending arm 74 pivotally connected by a link 75 to an arm 76 of an upstanding control lever 77 pivotally mounted at one side of the feeder head. Said bell cranks also have downwardly extending arms 78, which are pivotally connected to opposite ends of a tie rod 79. The arrangement just described provides interlocking control means which permits actuation of the positive clutch discs 55 by manipulating either one of the two control levers 77, 77 at opposite sides of the feeder head, but insures unclutching of one winding drum whenever the other drum is in positive clutched engagement with its respective drive sleeve.

40 45 50 55 60 65 70 75 75 Each of the sluing cables 36 is preferably trained from its respective winding drum 27 over two idler sheaves 81, 81 mounted toward the front of frame 28 so as to lead said cable into an opening 82 cut away from the outer side of the tubular torsion rod 70. Each cable is then carried to the front end of its rod, and is trained over two idler sheaves 83, 84 on the feeder head, arranged to permit said cable to be extended away from the feeder head at any desired angle. In

the form shown herein, the sheaves 83 are mounted in hooded extensions 85 formed integral with the bearing supports 72 in which the front ends of the tubular torsion rods 70 are journaled.

The bearing support 72 with the hooded extensions 85 are removable from the conveyor structure when desired. In the form shown herein, these parts are mounted on auxiliary frames 86, 86 detachably connectable to opposite sides of the feeder head 23 as by bolts 87 and with a tie rod 88 extending beneath the trough section 12 to connect said auxiliary frames together for additional support.

The use and operation of the apparatus is as follows:

The conveyor is set up in a mine in the usual manner with the shovel 22 of extensible trough 21 in position to load out loose material broken down from the working face, the base 14 of the swivel joint 11 jacked to the mine floor, and the main trough line 10 leading to a suitable point of discharge. The sluing cables 36, 36 are anchored to suitable abutments, such as mine jacks, at opposite sides of the conveyor. Said cables may be disposed at varying angles to the conveyor, depending upon mining conditions.

The feeder head 23 is operated as usual to gather up the loose material by gradual extension of the extensible trough 21, controlled in the usual manner by the manipulation of grip blocks 26 on said feeder head. During reciprocation of the conveyor, the rack bar 37 is held stationary due to its pivotal connection to the anchored cross bar 16, on which the swivel joint 11 is slidably mounted, while the frame 28 carried on the intermediate trough section 29 reciprocates with the main trough line of the conveyor. This relative motion between the rack bar and the trough section causes oscillation of the idler pinions 38 and, through said pinions, the gear sectors 40, drive discs 40a, drive members 41 and drive sleeves 42 are oscillated about their respective upright axes. The load limit devices 41a protect the drive mechanism against damage in case of excessive loads on the two drum driving mechanisms. The oscillating motion of the drive sleeves 42 is transformed by one-way clutches 49 into intermittent one-way rotation of the clutch sleeve 46, in the direction tending to wind the sluing cables 36 on their respective drums 27.

The brake pads 61 are set with relatively light yielding engagement with the drums 27 sufficient to resist unwinding thereof, but the friction discs 60 carried on the clutch sleeves 46 are of larger area and are designed to exert greater torque on the drums, sufficient to overcome the braking effect of brake pads 61, and tend to rotate the drums with enough torque to take in any slack in the cables. This frictional torque effect on the drums is not, however, sufficient to slue the conveyor or interfere with the normal shaking motion of the latter.

Therefore, when the clutch discs at both sides of the sluing mechanism are in intermediate position, unclutched from positive driving connection with their respective drums, the sluing cables 36 will be automatically maintained in taut condition while the conveyor proceeds to operate with its loader head 13 disposed in one angular position relative to the swivel 11.

When it is desired to shift the loader head laterally in one direction or the other, the operator manipulates either one of the interlocked control levers 71 so as to engage the clutch disc 55 on the side toward which he desires to slue the

loader head. Thereupon, the cable drum 27 on that side will be positively driven through the intermittent one-way rotation of its clutch sleeve 46, while the opposite drum would still be disengaged from positive drive. The actuating link 20 with its rack bar 37 swings laterally with the swivelling loading end of the conveyor to accommodate itself to all angular positions of the latter.

When it is desired to slue the feeder head in the opposite direction, the operator manipulates either of the control levers 71 in the opposite direction. The levers are restored to their intermediate unclutching position to discontinue sluing in either direction.

It will now be understood that the sluing cables 36 are automatically taken up and maintained in that condition at all times that the conveyor is being reciprocated, and also that one or the other of said sluing cables can be positively drawn in at will to slue the swivelling loading end of the conveyor in either direction as desired. Power for this sluing action is derived directly from the reciprocating motion of the conveyor trough as a whole. A more positive sluing motion is assured than in sluing devices previously proposed, wherein the sluing action is wholly dependent upon relative telescopic movement between the extensible trough 21 and the adjacent trough section 12 during the feeding operation, which movement in turn is dependent upon the frictional resistance of the extensible trough 21 with respect to the ground, when it is released from the grip blocks of the feeder head during forward or reverse stroke of the conveyor. Accordingly, the sluing mechanism of the present invention is operable independently of the feeder head; in fact, it can be employed with shaker conveyors having no extensible feeder head.

The arrangement whereby the winding drums 40 and their associated driving devices are mounted on the detachable intermediate trough section 29 facilitates the assembly of the sluing mechanism with a conventional shaker conveyor structure, and also permits the intermediate trough section 30 with the sluing mechanism to be bodily removed from the trough line for repairs, or when said sluing mechanism is not needed in a particular shaker conveyor set-up.

The arrangement whereby the sluing cables 36 are led forwardly from the winding drums to be paid out or drawn in from the feeder head 23 not only increases the efficiency of the sluing cables but protects the cables against fouling where they pass along opposite sides of the trough. Moreover, the extension of the clutch control mechanism to the control levers 71 on the feeder head places said control levers closely adjacent the hand levers which control the operation of the feeder head, so as to facilitate all 60 the feeding operations of the shaker conveyor by one operator.

Since the winding drums 27 and the frame 28, upon which they are supported, are mounted on the intermediate trough section 29, which trough section is detachably connectable in the trough line, as previously described. It will be noted that the entire intermediate trough section can be inserted in or removed from the trough line at will. Also the auxiliary frames 86, which carry the control lever 71, and the idler sheaves 83, 84, over which the sluing cables are paid out from opposite sides of the frame, can be attached to or disconnected from the feeder head 23 at will. Accordingly, the entire sluing mechanism dis- 75 closed herein may be readily applied as attach-

ments to a conventional shaker conveyor construction. Also the sluing mechanism can be removed from a conventional shaker conveyor when it is not required, without affecting the normal operation of the conveyor.

Although we have shown and described certain embodiments of our invention, it will be understood that we do not wish to be limited to the exact construction shown and described, but that various changes and modifications may be made without departing from the spirit and scope of the invention as defined in the appended claims.

We claim:

1. In a shaker conveyor having a laterally swivelling reciprocable trough, an anchoring support affording reciprocable movement of the swivelled joint, an extensible trough telescopically mounted at the end of said reciprocable trough line having a slideable ground supporting shoe at its inner end, feeder mechanism for controlling relative telescopic movement of said troughs connected to the reciprocable trough and slideably supported on said extensible trough intermediate the ends of the latter, the combination of a pair of winding drums mounted on the swivelling portion of the reciprocable trough intermediate the swivelling joint of the latter and the limit of inward telescoping movement of the extensible trough, each of said winding drums having sluing cables wound independently thereon adapted for connection to fixed abutments at opposite sides of said troughs, a rotatable drive member for each of said drums, a drive link means pivotally connected at one end to said swivelling trough portion and at the other end to said anchoring support for rotating said drive members in response to movement of said swivel-

ling trough relative to said anchoring support, and one-way clutch means affording selective positive driving connections between each of said drive members and their respective drums.

5. 2. Apparatus in accordance with claim 1, wherein the means pivotally connected to the anchor support consists of a link connected at one end to said anchor support and having a rack bar pivoted on its other end and slideably mounted on the swivelling end of the reciprocable trough, for engagement with said drive members.

10. 3. Apparatus in accordance with claim 1, wherein manual control means for the clutch means includes manually operable levers mounted on the feeder mechanism, a pair of shafts extending longitudinally of the reciprocable trough, and axially movable by said levers to actuate the clutch means.

15. 4. Apparatus in accordance with claim 3, wherein guide sheaves for paying out the sluing cables are mounted on the feeder mechanism, and the shafts are tubular, with the sluing cables threaded therethrough to provide guide means from adjacent the winding drums to the guide 20. 25 sheaves on the feeder mechanism.

ERNST R. BERGMANN.
